UNITED STATES PATENT OFFICE.

DANIEL H. TWAITS, OF CHICAGO, ILLINOIS.

OIL-CUP.

1,202,924.

Specification of Letters Patent. Patented Oct. 31, 1916.

Application filed January 31, 1914. Serial No. 815,684.

To all whom it may concern:

Be it known that I, DANIEL H. TWAITS, a citizen of the United States, residing at Chicago, in the county of Cook and State 5 of Illinois, have invented a certain new and useful Improvement in Oil-Cups, of which the following is a full, clear, and exact description, reference being had to the accompanying drawings.

10 This invention relates to oil cups of a type having a tubular body or cup portion opening upwardly and having a cover adapted to be opened for filling the cup, said cover being closed and held in its closed position 15 by the action of the spring within the oil cup.

The object of the invention is to provide a simple, efficient and durable spring which may be very cheaply manufactured, and 20 which may be replaced in case it should be broken by the use of extraordinary force.

25 My invention is hereinafter more fully described in connection with the drawings and the essential characteristics set forth in the claims.

In the drawings, Figure 1 is a side elevation of the oil cup; Fig. 2 is a central vertical section showing the spring for closing the cap; Fig. 3 is a central vertical section 30 showing a modified construction of the spring; Fig. 4 is a vertical section taken at right angles to the plane of Fig. 3, showing an elevation of the same spring; Fig. 5 shows a modified construction in which the 35 spring and cap are integral; Fig. 6 is a vertical central section through a cup formed in the shape of an elbow showing the form of a spring shown in Fig. 1, adapted for this cup; Fig. 7 is a vertical section through an 40 elbow cup showing the spring similar to that in Fig. 2 mounted therein.

In the drawings, 10 indicates the body portion or cup having a threaded portion 11 at its lower end and an intermediate angular 45 portion 12 by which it may be screwed into position. At the upper end, the cup opens upwardly and is normally closed by a cover 14 having a downwardly turned flange 15 extending partly around the cover. The effect 50 of the flange is to position the cap when drawn to closed position and add to the ap-

pearance of the cup. The spring for holding the cap or cover in position is a flat leaf spring 18 having a portion 20 at its upper end lying contiguous with the under side 55 of the cover and adapted to be secured thereto in any suitable manner. As shown, a rivet 21 is passed through the spring and cover, but any suitable means may be used for securing the spring to the cover, as, for 60 example, this portion of the spring may be electrically welded to the cover, or have an upwardly turned flange passing through the cover and upset at its upper end. The spring has a narrowed intermediate portion 65 and is made integral with two outwardly extending wings 23 at its lower end, which lie in a slightly enlarged bore 24 on the interior of the oil cup. When the spring is in position, these wings, which are bent to conform 70 to the surface of the bore 24, tightly engage such surface by tending to spring outwardly, and their upper edges engage the shoulder 25, preventing their upward movement within the cup. The spring is so bent 75 that it tends to draw downwardly, thereby pulling on the cap 14 and snugly holding the same in position, while it allows the cap to be pushed across the top of the cup (as indicated by dot and dash lines in Fig. 2), 80 thus providing an opening through which the cup may be filled. The raised lip 26 on the edge of the cover provides for pushing the cover to the open position by the spout of an oil can, if desired. As soon as 85 the cover is released, the action of the spring is to draw it back, sliding it across the top of the cup, to its closed position. A suitable notch is made in the upper edge of the 90 cover to clear the spring and the means for 95 securing it to the cover, as indicated at 28.

A modified construction of the lower end of the spring is shown in Figs. 3 and 4, in which, instead of the curved wings 23, straight wings 30 are provided, which engage slots 31 at each side of the cup. At 95 the upper edge of each of these wings is formed a squared shoulder 32, one portion of which engages the upper end of the notch and the other portion the inner surface of 100 the cup, tending to center the wings of the spring and preventing the same engaging

the threads and thereby injuring them while being screwed into position.

In Fig. 5 is shown a modified construction of the spring, which may be used with either of the forms just described, and consists in making the spring and cover of one strip of metal formed into substantially the shape shown, and having a portion integral with the edge of the cover opposite the flange 15, and extending inwardly along the under surface of the cover and then downwardly, forming the main portion of the spring, as in the other forms.

In Fig. 6, the spring 18 is given a curve at its upper edge, similar to the curve in the first forms described, and then, an opposite curve 38 at its lower end, bringing this end of the spring into position to lie substantially parallel with the axis of the threaded portion, as indicated at 39. In this form the spring is provided with wings similar to the wings 30 adapted to be tightly driven into slots 31 formed the same as the slots shown in Figs. 3 and 4. This allows the spring to press the cap into closed position, that is, the spring acts toward the right in this figure.

In Fig. 7, the body portion of the spring is given a curve similar to the curve 38 in Fig. 6, but the spring is secured to the cup by means of wings 40 similar to the wings 23 which engage an enlarged portion 42 of the bore on the interior of the cup, and rest against a shoulder 43, which prevents the wings sliding toward the upper end of the cup while the wings 40 themselves tightly engage the inner surface of the bore 42 by spring action, thereby securely holding the same in place. To more securely hold them, a suitable rivet as shown at 44, may be passed through one or both of the wings.

In each of the forms described, the spring is so bent that it pulls downwardly on the cap or cover, holding the same tightly in place, and it is so constructed that it may be bent, allowing the cover to be slid across the top of the cup a distance great enough to provide an opening for filling, while not allowing the cover to become displaced. In each construction, the spring acts to return the cover to closed position as soon as it is released.

Having thus described my invention, what I claim is:

1. In an oil cup, the combination of a cup portion, a cap, a leaf spring secured to the cap at one end and to the cup at the other end tending to draw downwardly on the cap while allowing it to be slid open for refilling.

2. In an oil cup, the combination of a cup portion, a cap for closing the upper end thereof, a leaf spring secured to the cap at one end and extending downwardly in-

side of the cup and having an engagement with the interior thereof and tending to draw the cap downwardly while allowing it to be slid across the cup against the tension of the spring.

3. In an oil cup, the combination of a cap portion having an open upper end, a cap for closing the upper end adapted to move laterally with reference to the cup portion, and a spring rigidly attached to the cap and extending downwardly inside of the cup and having its lower end secured to the lower end of the cup, said spring exerting a lateral tension on the cap.

4. In an oil cup, the combination of a cup portion having an open upper end, a cap adapted to close the same, a flat spring member rigidly secured to the cap near one edge thereof and extending downwardly within the cup and having wings at its lower end engaging the lower end of the cup, said spring member tending to draw downwardly on the cap and exerting a lateral tension on the same.

5. In an oil cup, the combination of a cup portion, a cap for closing the upper end thereof, a flat spring secured to the cap near one edge thereof and curving inwardly and downwardly within the cup and having outwardly extending wings at its lower end engaging the interior of the cup, said interior being provided with a shoulder against which said wings engage preventing their upward movement, whereby the spring may act to draw downwardly and laterally on the cap.

6. In an oil cup, the combination of a cup portion having an open upper end, a cap adapted to close the same and having a downwardly turned flange extending partly around the same, and a spring attached to the cap near the side opposite the flange and curving inwardly and downwardly and having outwardly extending wings at its lower end engaging the interior of the cup.

7. The combination of a cap for an oil cup and a spring member integral with the cap at one edge thereof and extending inwardly and curving downwardly and adapted to extend into the cup and having means at its lower end for securing it to the cup.

8. In an oil cup, the combination of a cup portion, a laterally movable cap therefor, a spring secured to the cap at one end and extending downwardly within the cup and having its other end engaging the cup and tending to draw downwardly on the cap while allowing it to be moved laterally for refilling.

9. The combination of an oil cup having an opening in the upper end, an external cap for said opening adapted to be slid across the same, and a spring member se-

cured to the closure and engaging the cup and adapted to allow the closure to be slid to uncover the opening.

10. In an oil cup, the combination of a cup portion having an open upper end, an external cap resting on and closing the upper end and slidable across the same, spring means tending to slide the cap toward its closed position, and means for stopping the

cap against the action of the spring when it reaches its normal closed position.

In testimony whereof, I hereunto affix my signature in the presence of two witnesses.

DANIEL H. TWAITS.
